UNITED STATES PATENT OFFICE.

JAMES B. RATTRAY, OF QUINCY, MASSACHUSETTS, ASSIGNOR TO GILLETTE SAFETY RAZOR COMPANY, OF BOSTON, MASSACHUSETTS, A CORPORATION OF DELAWARE.

DESIGN FOR A CASE FOR SAFETY RAZORS.

60,262.

Specification for Design.

Patented Jan. 17, 1922.

Application filed March 12, 1921. Serial No. 451,824. Term of patent 14 years.

To all whom it may concern:

Be it known that I, JAMES B. RATTRAY, a citizen of the United States, residing at Quincy, in the county of Norfolk and State of Massachusetts, have invented a new, original, and ornamental Design for Cases for Safety Razors, of which the following is a specification.

A case embodying my design is shown in the accompanying drawing, in which the figure is a perspective view of the case as it appears when open.

I claim:

The ornamental design for a case for safety razors, as shown.

JAMES B. RATTRAY.
